UNITED STATES PATENT OFFICE

2,519,664

HOLLOW CONCRETE BUILDING BLOCK

Harry Klein, Brooklyn, N. Y.

Application December 11, 1945, Serial No. 634,164

1 Claim. (Cl. 72—41)

1

This invention relates to bricks or building blocks, and has for its primary object the provision of an article of this character so constructed that when employed for building purposes a sturdy, fire-safe and well insulated construction results.

The invention further contemplates a brick which can be cast or moulded with a minimum of material, yet which will result in an article of maximum size, said article being easy to handle and to lay due to its shape and self-aligning features.

It is another object of the invention to provide means requiring only a minimum of mortar, possessing a high degree of insulation and contributing to speedy working conditions for the erection of building walls.

More particularly, the invention contemplates a brick of hollow or two-cavity construction formed with a top wall having recesses by which the brick may be conveniently handled and positioned during the laying operation; which has interior surfaces facilitating a firm and easy grasp by the fingers during handling; which has inclined faces defining the cavities to render the separation of the bricks from the mould cores a relatively simple procedure, and which has reinforcing ribs disposed at points whereat reinforcement is best required, said ribs being adapted to co-operate with complementarily-shaped recesses formed in one of the brick surfaces to assure proper alignment of the bricks when laid and to greatly speed up the laying operation.

These and other features and advantages will become more apparent from the ensuing description of the invention, and will be further clearly understood by referring to the accompanying drawing.

In the accompanying drawing, one of many possible embodiments of the invention is disclosed:

Fig. 1 is a bottom plan view of a brick or building block made according to the invention.

Fig. 2 is a top plan view of the brick seen in Fig. 1.

Fig. 3 is a longitudinal sectional view through the brick.

Fig. 4 is a sectional view taken on line 4—4 of Fig. 3.

Fig. 5 is a sectional view taken on line 5—5 of Fig. 3.

Fig. 6 is a front view, with parts in section of several bricks in a wall construction.

Referring now more particularly to the drawing, and especially to Figs. 1 to 3 inclusive, a

2

molded brick or building block is shown whose body is provided with longitudinal side walls 1 and 2, end walls 3 and 4, a cross web or partition 9 and a top wall 16.

5 A pair of cavities or passageways, indicated by numerals 5 and 6 extend into the body of the brick. It will be observed that the inner wall surfaces 7 and 8 which define the cavities are inclined and converge from the bottom 16a of the brick toward said top wall 16, this arrangement facilitating the movement of the mold or mold parts relatively to the brick body when the latter is formed and the mold parts or cores are to be removed therefrom.

15 The top wall 16 of the brick is formed with a pair of elongated openings 10 and 11, each of said openings being located centrally with respect to said cavities 5 and 6, respectively, and communicating therewith. The openings 10, 11 are 20 reduced with respect to the cavities, so that a flange 12 is provided around each opening, the face of each flange being arcuate, preferably convexly curved from the top wall 16 of the brick toward the inner wall surfaces 7, 8 which define the aforesaid cavities 5 and 6.

25 Web or separating partition 9 is provided to extend substantially centrally of said brick, opposite faces of said web being each provided with a vertically and centrally disposed, rounded reinforcing rib 13, one of each of these ribs being thus located to project into a respective cavity 5, 6. The ribs 13 which extend on opposite faces of the web or partition 9 are interconnected by rib portion 14, said portion serving as an aligning member when the bricks are laid in the normal staggered manner, as illustrated in Fig. 6. The inner wall face of each of the end walls 3 and 4 is provided with a vertically disposed rounded reinforcing rib 15, which substantially corresponds to 30 reinforcing rib 13.

35 Formed in the top wall or top face 16 of the brick and adjacent the opposite end walls 3 and 4 of the brick, is a groove 17 adapted to accommodate at least a part of the rib 14 of an adjacent brick laid on top of another brick and in the normal staggered relation as seen in Fig. 6.

40 From the foregoing, the manner in which the bricks are employed, will be readily understood. The bricks are intended to be laid on top of one another in the normal staggered manner with the mortar placed between them in a relatively thin layer. In placing the bricks on top of one another in the manner mentioned, it will be noted that the rib portion 14 on the bottom of the 45 upper brick (a, (Fig. 6), projects beyond the bot-

tom of said brick, and that said rib 14 will thus register with and fit into two end grooves 17 located in the top wall adjacent the ends of two lower bricks. While the engagement of the rib 14 with and penetration thereof into such adjacent grooves 17 may be relatively slight, it is nevertheless sufficient to materially aid in the placement and proper alignment of one brick on top of another, with the result that the bricks will not only be properly aligned but the brick-laying operation will be greatly speeded up.

The hollow nature of the brick described provides insulation characteristics and the internal reinforcement of the brick by tapering walls reinforced by the vertical ribs, provides a brick of exceptional strength for the amount of material employed in it. The apertures or openings 10 and 11 in the top wall of the brick and the particular shape of the flanges 12 thereon provide convenient finger stalls to which two fingers of a workman's hand may be applied to easily grasp and handle the brick. It will be observed that the convex surface on flange 12 not only facilitates easy manipulation by the fingers of a hand inserted through the openings 10 and 11, but provides also a tapered reinforced wall with an enlarged area on the top of the brick for application of the mortar thereto.

While the various outer surfaces of the described brick are shown as being relatively smooth, it will be obvious that the surface at the bottom of the brick may be left relatively rough to facilitate interlocking action between the mortar 29 placed in contact with such surface. For example, the lower face of the brick, around the larger ends of the cavities 5 and 6 might be left relatively rough for the purpose mentioned. These and other modifications are contemplated as being within the scope of the invention and the claim appended hereto.

It is apparent that any suitable concrete material may be employed to arrive at the particular detailed brick structure herein disclosed.

While there have been shown and described and

pointed out the fundamental novel features of the invention as applied to the above embodiment, it will be understood that various omissions and substitutions and changes in the form and details of the device and methods above described and illustrated may be made by those skilled in the art without departing from the spirit of the invention.

Having thus described the invention, what is claimed as new and desired to be secured by Letters Patent, is:

A building block comprising a body having opposed faces and provided with cavities passing from one of said faces into said body and providing elongated openings at said one face, an arcuate flange defining each opening and positioned below said one face, a transverse web disposed between said cavities, a reinforcing rib extending from said flange lengthwise of said web and over one end of the latter, a portion of said rib projecting outwardly beyond the other face of said body, the one face being provided with opposed end grooves spacedly arranged from said openings of said one face, said end grooves being disposed along the central longitudinal axis of said openings and being complementary in cross-section to said projecting rib portion to constitute a seat for at least a part of the rib portion of an adjacent body.
